UNITED STATES PATENT OFFICE.

FRANK H. KEITH, OF JOLIET, ILLINOIS.

LOCK FOR ELECTRIC SWITCHES.

1,202,071

Specification of Letters Patent. Patented Oct. 24, 1916.

Application filed August 12, 1915. Serial No. 45,158.

To all whom it may concern:

Be it known that I, FRANK H. KEITH, a citizen of the United States of America, residing at Joliet, county of Will, and State 5 of Illinois, have invented certain new and useful Improvements in Locks for Electric Switches, of which the following is a specification.

The present invention is directed to protective casings for switches of coil boxes, commonly used on automobiles, and has for its object to so construct a device of this character that it can be easily and quickly attached to the front of the coil box, and 15 when in place thereon will prevent an unauthorized person from actuating the switch.

A further object of the invention is to provide a casing of this nature which is so 20 constructed that the same can be attached to the coil box in a manner so that the same cannot be removed therefrom.

A still further object of the invention is to provide a casing of this nature having 25 combined therewith a lock barrel which necessitates the use of a certain key, whereby the barrel cannot be actuated to operate the switch until the proper key has been inserted therein.

30 With these and other objects in view, this invention resides in the novel features of construction, formation, combination and arrangement of parts to be hereinafter more fully described, claimed and illustrated in 35 the accompanying drawing, in which:—

Figure 1 is a vertical central sectional view through the casing, showing the same attached to the coil box. Fig. 2 is a side elevation of the casing. Fig. 3 is a vertical central sectional view through the casing and key barrel, the switch not being shown. Fig. 4 is a sectional view through the casing, similar to Fig. 3, but taken at right angles thereto. Fig. 5 is a rear view of the 45 attaching plate. Fig. 6 is a front view of the switch actuating disk. Fig. 7 is a vertical sectional view through the same. Fig. 8 is a vertical sectional view through the attaching plate and front wall of the coil box, showing one of the ears in its operative position, and the other in its inoperative position.

Referring to the drawing 1 indicates the coil box, which is of the conventional form, 50 and is supported by the dash board of the automobile in the usual manner, and has

fixed to its front wall the switch casing 2, and in which is mounted the usual switch mechanism 3. The protective casing 4 is of such size that the same can be placed over 55 the switch casing 2, and is provided with enlarged portions 5 having threaded sockets 6 formed therein for engagement by the screws 7, which serve to hold the casing 4 in place. When it is desired to apply the 60 casing 4, the coils are removed from the box 1, after which the front wall thereof is bored so that the screws 7 can pass therethrough and enter the sockets 6. Before the screws 7 are applied, the arcuate plate 76 78 is placed against the inner surface of the front wall of the box; said plate being provided with struck-out ears 9, whereby openings 10 are provided for the entrance of the screws 6, the heads of which being too large 71 to pass through said openings. After the screws 7 are properly placed, the ears 9 are bent against the heads thereof, thereby concealing the screws.

The inner surface of the front wall of the 80 casing 4 is provided with an annular flange 11, which forms in conjunction with the barrel 12 an annular recess 13, and into which is poured Babbitt metal, which serves 85 to hold said barrel rigidly in place. Rotatably mounted in the barrel 12 is a key 90 barrel 14, the inner end of which has fixed thereto a disk 15, said disk having its outer face provided with spaced lugs 16, which are adapted to engage the usual switch 95 mechanism 3 so that when the key barrel 14 is rotated the switch mechanism will be similarly actuated to open or close the circuit through the coils, as desired. The key barrel is constructed in the usual manner 100 and is adapted to contain tumblers which can be actuated only by an especially made key, and since the key barrel is of a well known make, a detail description of the same is not thought necessary.

From the foregoing description it will be seen that a protective casing has been provided which can be easily and quickly placed over the usual switch casing of a coil box, and when in place thereon the lugs 105 16 will interlock with the usual switch mechanism 3 so that when the disk is rotated upon the insertion of a proper key 17 in the key barrel, the switch mechanism will be actuated as desired.

110 What is claimed is:—
A locking attachment for winged switch

mechanism comprising, a cover adapted to be positioned over the winged switch mechanism, said cover having a central opening and a depending flange surrounding the opening, a barrel positioned in the central opening and having flanges engaging the outer surface of the cover for holding the barrel in position in said opening, a key barrel within the first mentioned barrel, means carried by the key barrel and engaging the winged switch mechanism for

imparting rotary movement thereto, and means engaging the flange and first mentioned barrel for securing the barrels in position.

15 In testimony whereof I affix my signature in the presence of two witnesses.

FRANK H. KEITH.
